UNITED STATES PATENT OFFICE.

AUGUSTUS W. VAUGHN, OF ADEL, IOWA.

PRINTING-PRESS.

No. 885,895.

Specification of Letters Patent.

Patented April 28, 1908.

Application filed December 1, 1903. Serial No. 183,414.

To all whom it may concern:

Be it known that I, AUGUSTUS W. VAUGHN, a citizen of the United States, residing at Adel, in the county of Dallas and State of Iowa, have invented certain new and useful Improvements in a Printing-Press, of which the following is a specification.

The objects of my invention are to provide a printing press of simple and durable construction which is comparatively inexpensive in its manufacture and at the same time will accomplish the work of a more expensive and larger press.

It is further my object to provide an over head arm for maintaining the printing roller in position relative to the type as this printing roller passes over said type.

A further object is to provide a mechanism which will automatically raise the frame over which the printing roller passes when said roller reaches its extreme outer limit of movement and maintain said frame in a raised position while the roller is moved to its point of starting and thus prevent the paper from being inked on the rear movement of the roller, and further to provide a mechanism for automatically releasing the frame from raised position and allowing it to move to its lowered position as the roller approaches its point of starting.

A further object is to provide a ball bearing roller which is designed to be placed on the ends of the shaft upon which the printing roller is mounted and is designed to engage the lower portions of the frames for maintaining said printing roller against vertical movement.

My invention consists in certain details in the construction, arrangement and combination of the various parts of the device, whereby the objects contemplated are attained as hereinafter more fully set forth, pointed out in my claims and illustrated in the accompanying drawings, in which—

Figure 1 shows a side elevation of the complete printing press. The dotted lines in this view show the different positions of the mechanism for raising and lowering the frame upon which the printing roller is mounted and the printing roller at its outer limit of movement in dotted lines. Fig. 2 is a cross sectional view of the ball bearing roller which

is mounted on each end of the shaft upon which the printing roller is mounted. This view shows said shaft in cross section also. Fig. 3 shows, in perspective, one end of the printing roller with the ball bearing roller mounted upon the shaft which bears it. Fig. 4 is a detail view of one end of the frame of the printing press and of one side thereof and is a cross section cut through the line 4—4 of Fig. 5. Fig. 5 is a plan view of the complete printing press. Fig. 6 is a cross sectional view of the printing roller and shows in cross section the mechanism for adjusting the paper in position on said roller. This view also shows a portion of one of the frames for holding the printing roller against vertical movement.

Referring to the accompanying drawings, I have used the reference numeral 10 to indicate the frame of the printing press which comprises four legs and connecting pieces between these legs. Mounted on the frame 10 and extending longitudinally of it are the tracks 11 and 12, each of said tracks having a rack 13 mounted thereon and extending longitudinally of them. The tracks 11 and 12 are pivotally mounted at 14 near the feeding end of the printing press and are thus mounted to allow the outer end of said tracks to be raised and lowered. The racks 13 are mounted on the outside of the top portion of the tracks 11 and 12 so as to form a flat surface inside of the racks upon which rollers hereinafter described are allowed to move as the printing roller is moved outwardly and inwardly on the racks 13. Mounted between these tracks 11 and 12 and near the central portion of them on the frame 10 is the form bed 15 designed to hold in position the forms of type and plate which are to be printed. Firmly attached to the outside portion of each of the tracks 11 and 12 respectively are the frames 16 and 17, said frames being designed to maintain the printing roller against vertical movement as it moves longitudinally of the printing frame.

Mounted on each of the racks 13 is a pinion wheel 18 designed to move longitudinally of said racks. Mounted between said pinion wheels and firmly attached to them is the shaft 19 upon which the impression roll 20 is mounted. This printing roller is of the ordi-

nary construction having an opening 21 in its periphery and having the grippers 22 rotatably mounted in one side of the opening, said grippers being designed to be swung by a 5 gearing to a position for maintaining the paper firmly relative to the impression roll as shown in Fig. 6 of the drawings. A further description of this is not deemed to be necessary as this form of impression roll is common 10 in various printing presses. Rotatably mounted on each end of the shaft 19 and adjacent to the pinions 18 are the arms 23, said arms extending inwardly from the impression roll and having the shaft 24 mounted between 15 their inner ends. Mounted between these arms 23 and on the shaft 24 are the flanged wheels 25 and 26 designed to move longitudinally over the inner portions 27 and 28 respectively of the tracks 11 and 12 20 as the pinions 18 move longitudinally of the racks 13.

Extending diagonally across the frame and rotatably mounted between the arms 23 and in the supports 36 and 37 which are attached 25 to said arm is the spreading roller 38, so constructed that it will not only rotate over the forms which are placed upon the form bed 15 as the impression roll is moved outwardly and inwardly, but it will also move from the 30 left to the right a slight distance and from the right to the left so that the ink will be evenly distributed over the forms.

Mounted on each end of the shaft 19 and outside of the pinions 18 is a ball or roller 35 bearing wheel 39 whose outer periphery is designed to engage the under portion of the frames 16 and 17 as the shaft is moved longitudinally of said frames, the inner portions of the rollers 39 which are adjacent to the 40 shaft 19 are cut away to receive the rollers or balls 40 which act on the interior of said rollers 39, and on the exterior of the shaft 19 as the shaft 19 is moved outwardly and inwardly above the frame 10. It will be seen 45 that as the shaft is rotated in one direction above the frame 10, the rollers 39 will be rotated in the opposite direction as they pass over said frame 10 as they engage the frame 16 and 17, thus rotating the rollers 39 in the same direction as the shaft 19 is rotated.

Mounted on the extreme right end of the shaft 19 is an arm 41, the shaft 19 being rotatable in said arm. Pivotaly attached to the inner end of said arm is a second arm 42 55 which is pivoted at its lower end to the frame 10. Rotatably mounted on the frame 10 and near its inner end is the gear wheel 43. Pivotaly attached to the gear wheel 43 and adjacent to the lower end of the arm 42 is an 60 arm 44 designed to swing the arm 42 on the pivot 45, and as the gear wheel 43 is turned. Rotatably mounted on the frame 10 and in mesh with the gear wheel 43 is the gear wheel 46 which is capable of being driven by means

of the crank 47 or from a power wheel. As 65 the gear wheel 46 is turned in one direction, the upper end of the arm 42 will be moved to its outer limit of movement and will correspondingly move the impression roll to its outer limit of movement, and as the gear 70 wheel 46 is rotated in the opposite direction, the upper end of the arm 42 will be moved inwardly and the printing roller will be also moved inwardly. Throughout the entire specification I mean by the inner end of the 75 machine that end where the papers to be printed are placed upon the machine.

Extending across the outer end of the frame and through the slots 48 in the tracks 13 is the rod 49 having the arms 50 firmly 80 mounted at each end thereof. At the lower end of each of these arms 50 is a curved slot 51 designed to receive the pins 52 which are on the frame 10. As the upper ends of the arms 50 are at their inner limit of movement, 85 the pins 52 will be at the inner ends of the slots 51 and the tracks 13 will be at their lower limit of movement. When the upper ends of the arms 50 are moved to their outer limit of movement, the pins 53 will be at the 90 outer ends of the slot 51 owing to the fact that swinging the upper ends of the arms 50 causes the lower portion in which the slots 51 are, to be moved inwardly, and as the slots 51 are curved upwardly from their inner 95 ends to their outer ends, the tracks 13 will be in a raised position when the pins 52 are at the outer ends of the slots 51.

Pivotaly attached to the upper end of one of the arms 50 is a rod 53 which extends longitudinally of the frame 16 and outside of it to the pivotally mounted lug 54 to which it is pivotally mounted. This lug 54 has its pivotal point 55 at its upper end and the arm 53 is pivotally attached to it at 56. The lower 100 end of the lug 54 extends below the portion of the frame 16 upon which the roller 39 rolls and is designed to be engaged by the shaft 19 as said shaft passes by it.

When the impression roll is moved to its 110 outer limit of movement, the shaft 19 engages the upper end of the arm 50 and causes it to be swung to its outer limit of movement and causes the outer end of the tracks 11 and 12 to be swung upwardly and the tracks will be 115 maintained in their position until the impression roll is drawn to its inner limit of movement, and the shaft 19 engages the lower end of the lug 54 which causes the upper end of the pivotally mounted arm 50 to 120 be drawn inwardly and thus lower the outer ends of the tracks 11 and 12.

Mounted above the upper inner portion of the frame 11 and at the rear of the frames 16 and 17 is a feeding table 57 inclined from its 125 inner end to its end adjacent to the frames 16 and 17. Hinged to the outer end of the feeding table 57 is a guiding plate 58 which is de-

signed to allow the printing roller 30 to be passed under it and to allow the papers to be printed to pass over the feeding table 51 and the guiding plate 58 into the grippers 22 which are mounted on the impression roll 20. Attached to the inner upper portion of the frames 16 and 17 and between said frames is the rod 59 having a series of guides 60 attached thereto, and extending outwardly and downwardly therefrom so that their lower ends engage the outer edge of the plate 58. These guides 60 are weighted so as to engage the plate 58 and constantly keep the paper being fed into the impression roll in a uniform position so that the grippers 22 on the printing roller 20 will grasp the paper and thus it will be wound around said roller. As the rod 59 is rotatably mounted, it will be seen that the lower end of the guides 60 will swing upwardly and downwardly and thus allow the paper to be passed between said guides and the plate 58.

In practical use, the operator places the paper to be printed on top of the feeding table 57 and operates the mechanism of the device by means of the crank 47, which operation causes the impression roll to be moved from its inner limit of movement after the paper has been engaged by the impression roll 20 and the grippers 22 over the forms of type which are mounted on the form bed 15 to the outer end of the frame 10. As it approaches the outer end of said frame, the shaft upon which the impression roll is mounted engages the upper end of the arm 50 which causes the said upper portion to be moved outwardly, which causes the outer end of the tracks 11 and 12 to be swung upwardly. Then by reversing the rotary movement of the crank 47, the impression roll moves inwardly until the shaft 19, upon which the printing roller is mounted, engages the lug 54, which causes the upper end of the arm 50 to be drawn inwardly, thus lowering the outer ends of the tracks 11 and 12 to move to their normal limit of movement, and the device is then in position for printing the next sheet. The ink cylinder 31 is constantly rotated on account of its engagement with the rollers 29 and 30 and a constant feeding of ink from the cylinder to these rollers is provided for.

Having thus described my invention, what I claim and desire to secure by Letters Patent of the United States, therefor is—

1. In a printing press, a frame, a track pivotally mounted upon which the impression roll of the press is designed to be mounted, an arm pivotally attached to said track, having a slot near its lower end, a pin in said frame and extending into said slot, so arranged that as the upper end of the arm is moved from its inner limit of movement outwardly, the track will be moved upwardly, and means

attached to the upper end of said arm for drawing it from its outer limit of movement inwardly for lowering the track from its raised position.

2. In a device of the class described, a frame, a track having two rails therein pivotally attached to said frame, a rack on each of said rails, a shaft having an impression roll mounted thereon, a pinion wheel at each end of said shaft and outside of said impression roll, each pinion being in mesh with the rack nearest it, an arm mounted on each end of said shaft, ink spreading rollers mounted between said arms, a ball bearing roller on each end of said shaft and outside of said arms, and a frame attached to each of said rails and in engagement with the ball bearing roller nearest it, and means for operating said shaft.

3. In a printing press, a track, a form bed mounted between the rails of the track, an impression roll, a shaft upon which the roll is mounted, frames mounted above the ends of the shaft and attached to the track designed to prevent the shaft from vertical movement, means designed to be operated by the shaft for swinging the outer end of the track upwardly and downwardly and means for operating the shaft.

4. In a printing press, a pivotally mounted track, an impression roll designed to move longitudinally of the track, frames connected with the track and designed to maintain the impression roll against vertical movement as it is operated longitudinally of the track, means designed to be operated by the impression roll for swinging the free end of the track upwardly and downwardly.

5. In a printing press, a pivotally mounted track, an impression roll designed to move longitudinally of the track, frames mounted outside of the track and designed to maintain the impression roll against vertical movement as it is operated longitudinally of the track, means designed to be operated by the impression roll for swinging the free end of the track upwardly and downwardly, a shaft upon which the impression roll is mounted, a ball bearing roller mounted on each end of the shaft and in engagement with the frame adjacent to it.

6. In a printing press, a pivotally mounted track, an impression roll designed to move longitudinally of the track, frames mounted outside of the track and designed to maintain the impression roll against vertical movement as it is operated longitudinally of the track, means designed to be operated by the impression roll for swinging the free end of the track upwardly and downwardly, a shaft upon which the impression roll is mounted, a ball bearing roller mounted on each end of the shaft and in engagement with the frame adjacent to it, said ball bear-

ing roller designed to be rotated constantly in the opposite direction from which the shaft is rotated as the shaft moves longitudinally beneath said frames.

- 5 7. In a printing press, a pivoted track, an impression roller designed to move longitudinally of the track, frames connected with the track and designed to maintain the impression roller against vertical movement

as it is operated longitudinally of the tracks 10 and means operated by the impression roll for swinging the track upwardly and downwardly.
